UNITED STATES PATENT OFFICE

153,642

DESIGN FOR A CHRISTMAS TREE ORNAMENT

Richard J. Silverman, Brooklyn, N. Y.

Application March 15, 1948, Serial No. 145,095

Term of patent 3½ years

(Cl. D29—1)

To all whom it may concern:

Be it known that I, Richard J. Silverman, a citizen of the United States, residing at Brooklyn, in the county of Kings and State of New York, have invented a new, original, and ornamental Design for a Christmas Tree Ornament, of which the following is a specification, reference being had to the accompanying drawing, forming part thereof.

In the drawing,

Fig. 1 is a front elevational view of a Christmas tree ornament, showing my new design.

Fig. 2 is a side elevational view of the Christmas tree ornament shown in Fig. 1.

I claim:

The ornamental design for a Christmas tree ornament, as shown.

RICHARD J. SILVERMAN.
